UNITED STATES PATENT OFFICE.

ALANSON CARY, OF NEW YORK, N. Y., ASSIGNOR TO AMERICAN FENCING COMPANY, OF SAME PLACE.

MACHINE FOR MANUFACTURING METALLIC BARBED RIBBON FOR FENCE-WIRE.

SPECIFICATION forming part of Letters Patent No. 226,034, dated March 30, 1880.

Application filed November 6, 1879.

To all whom it may concern:

Be it known that I, ALANSON CARY, of the city, county, and State of New York, have invented a new and useful Improvement in 5 Machines for Manufacturing Metallic Barbed Ribbon for Fence-Wire, of which the following is a specification.

The object of my invention is to construct a machine for manufacturing metallic barbed 10 ribbon for the wire used for fences so as to give to such wire a barbed edge; and the invention consists in a machine combining a reciprocating head carrying the cutters, a feed-bed, and die-plate, feeding-rollers, and an in- 15 tervall feed motion, whereby the ribbon is fed forward beneath the cutters and the operation performed rapidly without waste of material.

The construction and operation will be more 20 particularly described with reference to the accompanying drawings, wherein Figure 1 is a front elevation of the machine. Fig. 2 is a rear elevation. Fig. 3 is a plan view. Fig. 4 is a sectional side elevation on line $x-x$ of Fig. 25 3. Fig. 5 is a plan view of the feed-bed and die-plate. Fig. 6 shows a piece of the ribbon after passing through the machine. Figs. 7 and 8 are detail views.

Similar letters of reference indicate corresponding parts.

A is the bed-plate of the machine, upon which is fixed the pillow-block a , that supports the feed-bed B, and is extended up and formed as a box, a' , for the horizontal driv- 35 ing-shaft b , that is fitted with a pulley, b' , for connection of the power by belt.

Upon the forward part of the box a' , above the bed B, is fixed a head, C, that carries in a dovetail recess the slide c , that is connected, 40 through the head C, to the shaft b by a crank-pin or cam, so that the slide c is vertically reciprocated by the revolution of shaft b .

Upon the bed-plate A, at opposite sides of the pillow-block a , are fixed the standards d 45 d' and e e' , which carry, respectively, the shafts f f' and g g' of the upper and lower feed-rollers, h h' and i i' , these feed-shafts of each pair of rollers being parallel with the driving-shaft b and the feed-rollers at oppo- 50 site sides of the bed B.

The shafts f f' of the feed-rollers h h' are at the delivery side of the bed B. The upper shaft, f , is sustained by the forward standard, d , in a box, f^2 , that is fitted to slide in a vertical slot in the standard, and is pressed down by a spiral or other spring, h^2 , so as to impart 55 pressure to the feed-rollers. The upper shaft, g , is sustained in the standard e by a sliding box, e^2 , in the same manner, except that instead of a spring there is a rod, k , fitted in the standard e , to rest on the box e^2 , and upon the head C is hung a hand-lever, l , resting on rod k , by which pressure may be given to the feed-roller i , for purposes hereinafter described.

The lower feed-rollers, h i' , are formed each 60 with a peripheral groove, as shown, of the width of the ribbon that is to be operated upon, and the upper rollers, h i , are formed of a width to enter the said grooves.

The intermittent feed motion is given during the upward movement of the slide c by mechanism at the back of the machine. (Shown in Figs. 2, 3, and 4, and next described.)

Upon the rear ends of the lower feed-shafts, f' g' , are fixed gear-wheels m m' , respectively, 75 which are connected by an intermediate pinion, n , that is fitted to revolve freely on a stud projecting from the block a . Upon either shaft, preferably f' , is fixed a ratchet-wheel, o , and the same shaft carries loosely an arm, p , upon 80 the outer end of which is a pawl, q , that is kept in contact with a wheel, o , by a spring, p^2 . This device constitutes a pawl-carrier that is operated by the rod r , which is connected to arm p and to a crank-pin on the driving-pulley b' , so that the feed-shafts f' g' are given 85 an intermittent revolution in the same direction at once. The shafts f' g' are geared to shafts f g by the gearing s s' and t t' , as shown, and the rod r may be fitted adjustably at its 90 connection to pulley b' or arm p , so that the amount of feed at each movement may be regulated.

In the lower end of the reciprocating slide c are fixed the cutters or punches u . These 95 are preferably three in number, and will be fitted adjustably in any desired manner, so that they may be set down to compensate for wear.

In Fig. 7 the manner of fitting the punches 100

- is shown, wherein they are clamped in a recess of the slide *c* by a plate, *u'*, with blocks intervening to retain them the proper distance apart, and are pressed down by screws *u*², fitted in slide *c*. The cutters *u* are each formed with a cutting-edge inclined at an angle of about forty-five degrees to the direction of the feed, so as to cut or nick the ribbon, as shown by Fig. 6, about half its width, more or less.
- 10 The feed-bed *B* is recessed to receive the fixed cutters *v*, forming the die-plate, which cutters are of the same shape as cutters *u*, and are clamped by a block that is to be set up and held by screws *v'*. (Shown in Fig. 8.)
- 15 Upon the bed-plate *B* are adjustable plates *w*, held by screws, between the edges of which plates the ribbon passes over the cutters *v*.
- In operation the metallic ribbon is entered between the rollers *i i'* across the bed *B* to the 20 rollers *h h'*, and during its passage is cut by the reciprocating cutters *u*. The feed takes place while the cutters *u* are rising, and each movement of the feed should carry the last cut portion a suitable distance beyond the 25 cutters. The action of the cutters tends to bend the cut portion down, which assists the cutting, but the ribbon is bent flat again by the feed-rollers *h h'*, so that it may be readily rolled for further manufacture.
- 30 In first feeding the ribbon as described, the end is to be inserted between the rollers *i i'*,

and the requisite pressure given by the lever *l* to carry the ribbon forward until caught by the rollers *h h'*. The lever *l* is then to be relieved, so that the feed will be accomplished 35 by the last-named rollers only. By these means the ribbon may be cut at its extreme end, and there will be no waste of material at its first entering. By relieving the entering rollers of pressure, as mentioned, there will be 40 no risk of buckling or strain by reason of inequalities of feed in the two sets of rollers.

The product of this machine is used in the manufacture of barbed fence-wire by winding around a core, as shown in my patent granted 45 July 15, 1879.

Having thus fully described my invention, I claim as new and desire to secure by Letters Patent—

The combination, in a machine for manufacturing metallic barbed ribbon for fence-wire, with the reciprocating and fixed cutters, the feed-bed, and the intermittent feed-rolls, of the entering feed-rolls, fitted with a device for imparting the required pressure and having an 50 intermittent revolution, as and for the purpose specified.

ALANSON CARY.
